UNITED STATES PATENT OFFICE.

AUGUST MARHENKE, OF KIEL-GAARDEN, GERMANY.

FUEL-INJECTING DEVICE FOR INTERNAL-COMBUSTION ENGINES.

1,180,169.

Specification of Letters Patent. Patented Apr. 18, 1916.

Application filed December 12, 1913. Serial No. 806,326.

To all whom it may concern:

Be it known that I, AUGUST MARHENKE, citizen of the German Empire, residing at Kiel-Gaarden, Germany, have invented certain new and useful Improvements in Fuel-Injecting Devices for Internal-Combustion Engines, of which the following is a specification.

The subject matter of this invention is 10 a fuel injecting device for internal combustion engines, which is intended to enable difficultly ignitable fuels to be used.

The invention will be described with reference to the accompanying drawing, in 15 which—

Figure 1 shows the fuel nozzle and a portion of the engine cylinder in a vertical section taken through the axis of the cylinder, the other portions of the apparatus being 20 illustrated diagrammatically, while Figs. 2 and 3 show diagrammatically portions of two other constructional forms.

The constructional form shown in Fig. 1 will be described first.

25 Into the cover B of the cylinder A of an injection internal combustion engine is built in the usual way the fuel injecting valve C. Into this valve, which is normally closed toward the interior of the cylinder by a 30 controlled fuel needle D, open, in addition to the pipe H for the compressed air for injecting the fuel, two fuel passages F and G, one of which (F) leads to the space above the atomizer disks of an ordinary disk 35 atomizer E, and the other passage (G) to an annular space c¹ immediately above the needle seat. The two fuel supply passages F and G are supplied through two pipes f¹ and g¹, which branch off from a pipe L 40 leading from the fuel pump (not shown).

In the branch pipe f¹ is fitted a non-return valve J, loaded with a spring i¹ and in the branch pipe g¹ is fitted a valve K, which a spring k¹ tends to close. This valve K 45 is so connected to the governor M of the engine, that when the load on the engine decreases it is opened from a certain position of the governor sleeve m¹ onward against the pressure of the spring k¹. For 50 this purpose the spindle k² of the valve K is connected to the piston rod n¹, of an auxiliary motor N worked by oil under pressure. The supply and discharge of the oil under

pressure is regulated by a distributing valve P operated by the governor M, and to which are connected a supply pipe q¹ for the oil under pressure and an exhaust pipe q², for the oil under pressure, and from which a pipe q³ for the oil under pressure leads to the space, in the auxiliary motor N, situated 60 above the piston. A spring n² acts upon the lower piston face of the auxiliary motor N.

The description of the working of the above described apparatus will be commenced from 65 the position of the various parts shown in Fig. 1, which is the position they assume when the engine is under a light load (from about half load or downward). The engine then runs at a fairly high number of revolutions 70 and the governor sleeve m¹ is comparatively high up. It has at the same time carried up with it the distributing valve P for the oil under pressure, and this latter has connected the supply pipe q¹ for the oil under 75 pressure through the pipe q³ with the auxiliary motor N, the piston of which has consequently moved downward and has opened the valve K with the simultaneous compression of the springs n² and k¹. As the valve 80 J is kept closed by its spring i¹, the fuel supplied by the fuel pump passes through L g¹ K g¹ G into the annular space situated above the seat of the needle and, on the opening of the fuel needle, the fuel is carried along by the compressed air for injection directly into the cylinder. From about half load or downward to no load at all, there is fuel close over the seat of the needle, so that even when the nozzle is completely 90 blown empty, miss fires are not to be feared.

If now the governor sleeve drops as the load increases the distributing valve P for the oil under pressure moves downward. As it does so it first cuts off the supply of 95 oil under pressure through the pipe q¹ to the auxiliary motor N, and then connects this latter with the discharge pipe q² for the oil under pressure. With the disappearance of the pressure acting upon the top 100 of the piston of the auxiliary motor N, the piston moves upward under the action of the expanding springs n² k¹, and the valve K closes automatically. The fuel now pursues its course over L J f¹ F over the disk 105 atomizer, and on the opening of the fuel

needle D the fuel is forced into the cylinder by the compressed air, after passing through the atomizer E.

The constructional forms diagrammatically shown in Figs. 2 and 3 differ substantially from the constructional example just described, in deriving from the valve shaft the power for holding open the valve K. In the constructional form shown in Fig. 2 a cam S, mounted on the valve shaft R, rocks an arm T, the pivot t^1 of which, when the governor sleeve m^1 is in the raised position, is held in such a position by a bell crank lever arrangement U U^1 that the contact edge t^2 provided on the other end of the arm T strikes against the valve spindle k^2 and pushes open the valve K at each revolution of the valve shaft and at the time of the fuel supply. When the load is great and the governor sleeve m^1 therefore in its low position, the pivot t^1 of the rock arm T is in such a position with relation to the valve spindle k^2 that the contact edge t^2 does not strike against the valve spindle k^2 at all. In the constructional form shown in Fig. 3, the pushing open of the valve K is effected through the medium of a pusher rod W, by a cam disk V mounted on the valve shaft R. The valve is however only opened when the engine is under a light load, that is to say when the governor sleeve m^1 is in a raised position, as it is only then that a wedge Z, operated by the governor, establishes the connection between the pusher rod W and the valve spindle k^2 .

The two constructional forms partially illustrated in Figs. 2 and 3 will therefore work in principle, in exactly the same manner as the constructional form illustrated in Fig. 1.

I claim:

1. In a fuel injecting device for internal combustion engines having an atomizer and a main fuel conduit, opening to the rear of the atomizer and an auxiliary fuel conduit, having an inlet opening in front of the atomizer; a spring loaded, non-return valve and a normally closed valve both in said auxiliary conduit and means for opening said valve when the engine is running with a light load, said means comprising a speed actuated valve.

2. In a fuel injecting device for internal combustion engines, having an atomizer and a main fuel conduit, opening to the rear of the atomizer and an auxiliary fuel conduit, opening in front of the atomizer; a spring loaded, non-return valve and a normally closed valve both in said auxiliary conduit and means for opening said second valve, said means being actuated by the governor of the engine, whereby said second valve will be opened only when the engine runs with a light load.

3. In a fuel injecting device for internal

combustion engines having an atomizer and a main fuel conduit, opening to the rear of the atomizer and an auxiliary fuel conduit, opening in front of the atomizer; a spring loaded, non-return valve and a normally closed valve, both in said auxiliary conduit and means for opening said normally closed valve when the engine is running with a light load; said means comprising a pressure fluid driven motor having positive connection with said normally closed valve, the admittance of pressure fluid into said motor being actuated by the governor of the engine.

4. In a fuel injecting device for internal combustion engines having an atomizer and a main fuel conduit, opening to the rear of the atomizer and an auxiliary fuel conduit, opening in front of the atomizer; a normally closed valve in said auxiliary conduit and means for opening said valve when the engine is running with a light load; said means comprising a pressure fluid driven motor having positive connection with said valve, a pressure fluid conduit leading to said motor and a valve in said pressure fluid conduit, said last named valve being opened by the engine governor when the load on the engine is light.

5. In a fuel injecting device for internal combustion engines having an atomizer and a main fuel conduit, opening to the rear of the atomizer and an auxiliary fuel conduit, opening in front of the atomizer; a spring-loaded, non-return valve and a normally closed valve both in said auxiliary conduit and means for opening said normally closed valve when the engine is running with a light load; said means comprising a pressure fluid driven motor having a piston positively connected with said normally closed valve, a spring acting on said piston in the direction of closing said valve, a pressure fluid conduit opening on the opposite side of said piston, a valve in said pressure fluid conduit, said last named valve being actuated by the engine governor, to admit pressure fluid into said motor and thereby opening said normally closed valve for admitting fuel in front of the atomizer, when the load on the engine is light.

6. In a fuel injecting device for internal combustion engines having an atomizer and a main fuel conduit, opening to the rear of the atomizer and an auxiliary fuel conduit, opening in front of the atomizer; a spring-loaded, non-returnable valve both in said auxiliary conduit and means for opening said normally closed valve when the engine is running with a light load; said means comprising a pressure fluid driven motor having a piston positively connected with said normally closed valve, a spring acting on said piston in the direction of closing said valve, a pressure fluid conduit opening

on the opposite side of said piston, a valve in said pressure fluid conduit, said last named valve being actuated by the engine governor, to admit pressure fluid into said 5 motor when the load on the engine is less than a fixed amount; and said last named valve being similarly actuated to expel pressure fluid from said motor, when the load on the engine exceeds said fixed amount,

thereby closing said normally closed valve 10 and admitting fuel to the engine through said main conduit only.

In testimony whereof I have affixed my signature in presence of two witnesses.

AUGUST MARHENKE.
